INTERNAL COMBUSTION ENGINE WITH PISTON HAVING COMBUSTION CAVITY IN ITS HEAD

Alberto Jorge Morris, Dursley, England, assignor to R. A. Lister & Company Limited, Dursley, England, a British company

Application June 21, 1954, Serial No. 438,198

Claims priority, application Great Britain May 3, 1951

22 Claims. (Cl. 123—32)

This invention relates to pistons of the type, herein-after referred to as the type specified, used in internal combustion engines and formed with a combustion-space cavity in the piston head, the wall of the cavity being undercut around the periphery of an inlet orifice to the cavity, and also relates to engines employing pistons of the type specified.

This invention is concerned with improvements in pistons of the type specified and in engines employing such pistons, and the features of improvement are directed to improving combustion of fuel or to avoiding disadvantages in the manufacture or use of pistons of the type specified.

According to the present invention, there is provided a piston of the type specified, wherein the inlet orifice to the cavity is formed by a throat tapering inwards towards the cavity, and wherein the wall of the cavity has a peaked land projecting from the bottom of the cavity towards the inlet orifice and has its surface formed as a surface of revolution whereof the axis of revolution is coaxial with said land and with the inlet orifice and whereof the generatrix is a line having a greater radius of curvature adjacent the land than adjacent the inlet orifice.

According to a feature of the invention, the generatrix of the wall is a portion of a spiral, or is formed by two arcs of different radii of curvature with the centre of curvature of the larger radius arc offset from the axis of revolution by an amount equal to the radius of the arc and with the centres of curvature of the arcs spaced apart by a distance equal to the difference in length of the radii of curvature so that the smaller radius arc is a continuation of the outer end of the larger radius arc, the smaller radius arc forming part at least of the cavity wall immediately surrounding the inlet orifice and the larger radius arc forming part at least of the cavity wall opposite the orifice.

The peaked land may be rounded off to have its truncated apex at a distance of about two-fifths of the radius of the larger arc below the plane containing the loci of the centres of the arcs. Alternatively, the apex can be flattened, or can be formed with a depression facing the orifice, or can be provided with a mushroom-shaped head.

According to yet another feature of this invention the diameter of the orifice giving access to the cavity in a piston of the type specified may be made small compared with the diameter of the piston. Preferably the ratio of the diameters lies within the range 0.15:1 and 0.25:1.

According to yet another feature of the invention, the inlet orifice giving access to the cavity in the piston may have the final entry portion of the inlet orifice tapered at an included angle of 15°.

According to yet another feature of the invention, to facilitate manufacture of the piston the orifice giving access to the cavity and the portion of the cavity wall immediately surrounding the orifice to the cavity may be formed by a ring secured in a threaded outer end of a

2

recess in the head of the piston, the bottom end of the recess either being shaped to afford the portion of the cavity wall opposite the orifice, or receiving a disc-like insert having one surface shaped to afford the portion of the cavity wall opposite the orifice and having, if desired, the opposite surface seating on the bottom of the recess over part only of its area, the bottom of the recess being for instance formed with a peripheral seating land.

Some embodiments of this invention will now be described with reference to the accompanying diagrammatic drawings in which—

Figure 1 is an axial section through an engine cylinder fitted with a piston of the type specified which embodies a number of novel features according to this invention.

Figure 2 is a view of the head of the piston illustrating other features of this invention.

Figure 3 is a view corresponding to Figure 1 of a modification.

Figure 4 is a view of a modification of the arrangement shown in Figure 3, and

Figure 5 is an axial section of an arrangement employing a spiral generatrix for the wall of the cavity.

Referring to the drawings, the engine comprises a cylinder 1 having a centre line 1a, a cylinder head 2 having formed therein a bore 4 to receive a fuel injector, the bore having a centre line 4a which is inclined to the centre line 1a but which is contained in a plane containing the centre line 1a and indicated in Figure 2 by the line 4b, an air inlet duct 6 which terminates in an air inlet port 5, the positions of these parts being indicated at Figure 2 showing that the air inlet port 5 and the air inlet duct 6 are so positioned that air entering the cylinder is given a rotary motion, as indicated by arrow 7, about the axis 1a of the cylinder, and a piston 3 which is flat-topped and has a cavity 8 formed in the head to afford a combustion space for the fuel being injected into the engine cylinder.

Access to the cavity 8 is obtained through an orifice 9, and the cavity 8 and orifice 9 are bounded by walls 8b, 10b and 9a which are surfaces of revolution about an axis 8a, the wall of the cavity being undercut as shown around the periphery of the orifice 9. The cavity 8 is bounded by walls 8b and 10b which are both surfaces of revolution of arcs of circles, the centre 8c of the arc for forming the wall 8b being offset from the axis 8a by an amount equal to the radius of the arc for forming the wall 8b, and the centre 10c of the arc for forming the wall portion 10b, which arc is of less radius of curvature than that for the wall part 8b, being disposed in the plane of the locus of the centres 8c and on the side of the centre remote from the axis 8a, the centres 8c and 10c being spaced apart by a distance equal to the difference in the radii of curvature of the arcs for forming the walls 8b and 10b. Thus the ends of the arcs for forming the walls 8b and 10b remote from the axis 8a meet in a common tangent.

By reason of the centre 8c being a distance from the axis 8a equal to the radius of the arc for forming the wall 8b there is formed at the centre of the cavity an upstanding land 11. In Figures 1 and 3, the land is peaked and is rounded off so as to terminate at a distance below the plane containing the centres 8c and 10c equal to about two-fifths of the radius of the arc for forming the wall 8b. In Figure 4 the land 11 is flattened and supports a peaked button 14 the purpose of which will be described more fully below.

The orifice 9 giving access to the cavity 8 is formed as a tapering throat, the entrance portion of the throat being rounded and the final inlet portion of the throat 9a being a cone having an apex angle of say 15°.

The tapering form of the orifice 9 causes acceleration of the gases flowing through the orifice 9 into the cavity 8

and the form of the cavity is such that very turbulent conditions are created within the cavity 8.

The orifice 9 has a throat diameter which is small compared with the diameter of the piston 3. The ratio of the diameter of the throat at the narrowest point to the piston diameter is conveniently within the range 0.15:1 and 0.25:1. The restricted form of the orifice 9 also assists in accelerating the gas flow into the cavity 8 and assists in increasing turbulence therein.

As will be seen from Figure 2, the axis 8a, which is indicated in Figure 2 by point A, is offset from the plane 4b containing the axis of the cylinder 1a and the axis 4a of the fuel injector bore and the amount by which it is offset is selected to accommodate for deflection of the fuel spray angularly with respect to the centre line 1a caused by the swirl (represented by arrow 7) of the gases entering the cylinder through port 5. As will also be seen from Figure 2 the axis 8a is offset from the plane through axis 1a at right angles to the plane 4b, the amount by which it is offset from this plane being selected so that fuel being injected into the cylinder can pass into the cavity 8 without impinging on the walls of the orifice 9.

In each of the arrangements illustrated, the wall portion 10b and the orifice 9 are afforded by a ring 10 threaded into the outer end of a recess cast or otherwise formed in the head of the piston 3; this arrangement facilitates manufacture of the piston. The ring 10 need not be of the same material as the piston 3, for instance the ring 10 may be made from a more heat-resistant material, for instance a ceramic material, than the piston 3, or may be coated with a highly heat-resistant material such as a ceramic material.

The wall portion 8b of the cavity 8 and the land 11 may be formed in a number of ways. Thus, referring to Figure 1, the bottom of the recess is shaped to afford the wall portion 8b and the land 11, and also to afford a shoulder 12 against which the ring 10 abuts when it is threaded into the recess.

Referring to Figures 3 and 4, the recess is substantially a cylindrical recess, and the wall portion 8b and land 11 are provided by inserting into the bottom of the recess a disc-like insert 15 having a suitable upper surface; the under surface of the insert 15 bears against the bottom of the recess and to assist to insulate the piston head from the cavity 8, the insert 15 is arranged to bear against the bottom of the recess over part only of its under surface, there being a peripheral seating land 16 around the bottom of the recess. The insert 15 is preferably made from a highly heat-resistant material and may for instance be made from a ceramic material and thus further insulate the cavity 8 from the piston head.

Referring now to Figure 4, the button 14 is made from a highly heat-resisting material and is a solid of revolution about the axis 8a. The button has a mushroom-shaped head and has a maximum diameter of about 0.15 to 0.25 times the diameter of the piston. The button is shaped to deflect the fuel spray impinging on it in an upward direction towards the surface 10b. The periphery of the button overhangs the land 11 and thus any fuel running down the surface of the button will fall into a turbulent zone adjacent the button periphery. The summit of the button is roughly level with the plane containing the centres 8c, 10c. The button 14 may as illustrated be formed separately from the insert 15 and attached thereto as by a rivet stem 14a, or may be made integral with the insert 15.

The button 14 assists in reducing ignition lag and combustion noise by improving mixing of the fuel and air in the cavity, and by retaining heat assists in ignition. The button arrangement is especially useful in small engines.

It is preferably arranged as shown for the centre line of the fuel spray to impinge on the apex of the land within a circle concentric with the cavity and having a radius

equal to $0.1r$, where r is the radius of the larger radiussed arc of generatrix of the cavity.

Instead of the generatrix of the cavity 8 consisting of two circular arcs, it may take the form of a spiral 17 as shown in Figure 5, the spiral increasing in radius of curvature from adjacent the orifice to adjacent the land. The arrangements of Figures 1 to 4 are however preferred since the machining is rendered easier.

I claim:

10. 1. An internal combustion engine piston having a piston head, whereof the end surface affords the crown of the piston, a combustion cavity in the piston head, an entry throat of circular section open at one end to the crown of the piston and at its opposite end to the cavity, said throat tapering from the crown to the cavity whereby gases entering the combustion cavity are accelerated in their passage through the throat, said cavity having its wall opposite the entry throat formed with a peaked land which projects towards the entry throat coaxially therewith, the wall of the cavity being formed as a surface of revolution whereof the axis of revolution is coaxial with said land and with the entry throat and whereof the generatrix is an arc having a greater radius of curvature beginning adjacent the land than adjacent the entry throat.
15. 2. A piston as claimed in claim 1 wherein the generatrix is a portion of a spiral.
20. 3. A piston as claimed in claim 1 wherein the arc which is the generatrix of the cavity wall has two portions, each portion being part circular and the portions having different radii of curvature, the centre of curvature of the larger radius portion being offset from the axis of revolution by an amount equal to its radius, and the centres of curvature of the two portions being spaced apart by a distance equal to the difference of the radii of curvature so that the smaller radius portion is a continuation of the outer end of the larger radius portion, the smaller radius portion forming at least that portion of the cavity wall immediately surrounding the end of the entry throat where it opens into the cavity, and the larger radius part forming a portion at least of the cavity wall opposite the orifice.
25. 4. A piston as claimed in claim 3, wherein the apex of the peaked land is at a distance of substantially two-fifths of the radius of the larger radius portion below the plane containing the loci of the centres of the two parts of the arc.
30. 5. A piston as claimed in claim 1 wherein the ratio of the diameter of the narrowest part of the entry throat to the diameter of the piston lies in the range 0.15:1 to 0.25:1.
35. 6. A piston as claimed in claim 1 wherein entry throat has a final entry portion which is tapered to be part of a cone having an apex angle of about 15°.
40. 7. An internal combustion engine piston having a piston head, whereof the end surface affords the crown of the piston, said piston head having formed therein a recess open to the crown of the piston, said recess having a threaded wall portion adjacent the crown, a second wall portion at the end of the threaded wall portion remote from the crown formed as an annular abutment facing towards the crown, and a third wall portion forming the end of the recess remote from the crown, said third wall portion being formed as a surface of revolution whereof the generatrix is substantially a first circular arc beginning adjacent the land and whereof the axis of revolution is coaxial with the threaded wall portion and annular abutment, the centre of curvature of the first circular arc being co-planar with the annular abutment and being offset from said axis of revolution thereby to form a peaked land coaxial with the recess projecting towards the crown of the piston, and a threaded insert engaging said threaded wall portion with its outer end level with the crown of the piston and its inner end abutting said annular abutment said insert having an inner surface remote from the crown formed as a surface
45. 8. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.
50. 9. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.
55. 10. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.
60. 11. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.
65. 12. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.
70. 13. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.
75. 14. A piston as claimed in claim 7 wherein the threaded wall portion is formed as an annular abutment facing towards the crown, the annular abutment being offset from the axis of revolution of the piston by an amount equal to the radius of the first circular arc of the generatrix of the cavity.

of revolution whereof the generatrix is substantially a second circular arc having a smaller radius of curvature than the first circular arc and whereof the axis of revolution is coaxial with said recess; the centre of curvature of the second circular arc being in the plane of said annular abutment and being offset from the axis of revolution by a distance which is greater than that by which the centre of curvature of the first circular arc is offset, the two said centres of curvature being spaced apart by an amount equal to the difference of said radii of curvature so that the two arcs form a smooth continuation of each other, said third wall portion of the recess and the inner surface of the insert together defining a combustion cavity, and the insert having formed therein an entry throat coaxial with said land and of circular section, the throat being open at one end to the crown of the piston and at its opposite end to the cavity, said throat tapering from the crown to the cavity and said second circular arc having an end portion adjacent said entry throat, which end portion extends in a direction towards the peaked land and defines a lip projecting into the cavity round said opposite end of the entry throat.

8. A piston as claimed in claim 7 wherein the insert is formed from a material having a high resistance to heat.

9. A piston as claimed in claim 7 wherein the insert is coated with a material having a high resistance to heat.

10. An internal combustion engine piston having a piston head, whereof the end surface affords the crown of the piston said piston head having formed therein a substantially cylindrical recess with a threaded wall; a cylindrical insert is disposed in the bottom of the recess, the insert having its end-face nearer the crown of the piston affording an annular abutment surface and within the annular abutment surface being formed as a surface of revolution whereof the generatrix is substantially a first circular arc and whereof the axis of revolution is coaxial with the abutment surface, the centre of curvature of the circular arc being substantially co-planar with said abutment surface, and being offset from said axis of revolution thereby to form an upstanding land projecting towards the crown of the piston coaxially with said cylindrical recess; and a threaded insert which is engaged with the threaded wall and abuts said annular abutment surface, the threaded insert having an inner surface remote from the crown formed as a surface of revolution whereof the generatrix is substantially a second circular arc having a smaller radius of curvature than the first circular arc and whereof the axis of revolution is coaxial with the cylindrical recess, the centre of curvature of the generatrix of said inner surface being co-planar with the annular abutment surface and being offset from the axis of revolution by a distance which is greater than that by which the centre of curvature of first circular arc is offset, the two said centres of curvature being spaced apart by an amount equal to the difference of the radii of curvature so that the two arcs form a smooth continuation of each other, said surfaces of revolution of the inserts together defining a combustion cavity, and said threaded insert having formed therein an entry throat coaxial with cylindrical recess and of circular section open at one end to the crown of the piston and at its opposite end to the combustion cavity, said throat tapering from the crown to the cavity, and said second circular arc having an end portion adjacent said entry throat, which end portion extends in a direction towards the peaked land and defines a lip projecting into the cavity round said opposite end of the entry throat.

11. A piston as claimed in claim 10 wherein the bottom of the recess is formed with a peripheral seating land for said cylindrical insert.

12. A piston as claimed in claim 11 wherein the upstanding land is provided with a mushroom-shaped head,

which is formed separately from the cylindrical insert and has a stem portion which is riveted in the cylindrical insert.

13. A piston as claimed in claim 10 wherein the inserts are formed from a material having a high resistance to heat.

14. A piston as claimed in claim 10 wherein the inserts are coated with a material having a high resistance to heat.

15. Internal combustion engine piston having a piston head, whereof the end surface affords the crown of the piston, a combustion cavity in the piston head, an entry throat of circular section open at one end to the crown of the piston and at its opposite end to the cavity, said throat tapering from the crown to the cavity whereby gases entering the combustion cavity are accelerated in their passage through the throat, said cavity having its wall opposite the entry throat formed with a peaked land which projects towards the entry throat coaxially therewith, the wall of the cavity being formed as a surface of revolution whereof the axis of revolution is coaxial with said land and with the entry throat and whereof the generatrix is an arc having a greater radius of curvature adjacent the land than adjacent the entry throat, said arc having an end portion adjacent the entry throat, which end portion extends in a direction towards the peaked land and defines a lip projecting into the cavity round said opposite end of the entry throat.

16. An internal combustion engine piston having a

30 piston head, whereof the end surface affords the crown of the piston, said piston head having formed therein a recess open to the crown of the piston, said recess having a threaded wall portion adjacent the crown, a second wall portion at the end of the threaded wall portion remote from the crown formed as an annular abutment facing towards the crown, and a third wall portion forming the end of the recess remote from the crown, said third wall portion being formed as a surface of revolution whereof the generatrix is substantially a first circular arc and whereof the axis of revolution is coaxial with the threaded wall portion and annular abutment, the centre of curvature of the first circular arc being co-planar with the annular abutment and being offset from said axis of revolution thereby to form a peaked land coaxial with the recess projecting towards the crown of the piston, and a threaded insert made of ceramic material engaging said threaded wall portion with its outer end level with the crown of the piston and its inner end abutting said annular abutment said insert having

35 an inner surface remote from the crown formed as a surface of revolution whereof the generatrix is substantially a second circular arc having a smaller radius of curvature than the first circular arc and whereof the axis of revolution is coaxial with said recess; the centre

40 of curvature of the second circular arc being in the plane of said annular abutment and being offset from the axis of revolution by a distance which is greater than that by which the centre of curvature of the first circular arc is offset, the two said centres of curvature being

45 spaced apart by an amount equal to the difference of said radii of curvature so that the two arcs form a smooth continuation of each other, said third wall portion of the recess and the inner surface of the insert together defining a combustion cavity, and the insert

50 having formed therein an entry throat coaxial with said land and of circular section, the throat being open at one end to the crown of the piston and at its opposite end to the cavity, said throat tapering from the crown to the cavity and said second circular arc having

55 an end portion adjacent said entry throat, which end portion extends in a direction towards the peaked land and defines a lip projecting into the cavity round said opposite end of the entry throat.

17. An internal combustion engine piston having a

75 piston head, whereof the end surface affords the crown

of the piston said piston head having formed therein a substantially cylindrical recess with a threaded wall; a cylindrical insert is disposed in the bottom of the recess, the insert having its end-face nearer the crown of the piston affording an annular abutment surface and within the annular abutment surface being formed as a surface of revolution whereof the generatrix is substantially a first circular arc and whereof the axis of revolution is coaxial with the abutment surface, the centre of curvature of the circular arc being substantially co-planar with said abutment surface, and being offset from said axis of revolution thereby to form an upstanding land projecting towards the crown of the piston coaxially with said cylindrical recess; and a threaded insert made of ceramic material which is engaged with the threaded wall and abuts said annular abutment surface, the threaded insert having an inner surface remote from the crown formed as a surface of revolution whereof the generatrix is substantially a second circular arc having a smaller radius of curvature than the first circular arc and whereof the axis of revolution is coaxial with the cylindrical recess, the centre of curvature of the generatrix of said inner surface being co-planar with the annular abutment surface and being offset from the axis of revolution by a distance which is greater than that by which the centre of curvature of first circular arc is offset, the two said centres of curvature being spaced apart by an amount equal to the difference of the radii of curvature so that the two arcs form a smooth continuation of each other, said surfaces of revolution of the inserts together defining a combustion cavity, and said threaded insert having formed therein an entry throat coaxial with cylindrical recess and of circular section open at one end to the crown of the piston and at its opposite end to the combustion cavity, said throat tapering from the crown to the cavity and said second circular arc having an end portion adjacent said entry throat, which end portion extends in a direction towards the peaked land and defines a lip projecting into the cavity round said opposite end of the entry throat.

35
40

18. A piston as claimed in claim 15 wherein the generatrix is a portion of a spiral.

19. A piston as claimed in claim 15 wherein the arc which is the generatrix of the cavity wall has two portions each portion being part circular and the portions having different radii of curvature, the center of curvature of the larger radius portion being offset from the axis of revolution by an amount equal to its radius, and the centers of curvature of the two portions being spaced apart by a distance equal to the difference of the radii of curvature so that the smaller radius portion is a continuation of the outer end of the larger radius portion, the smaller radius portion forming at least that portion of the cavity wall immediately surrounding the end of the entry throat where it opens into the cavity, and the larger radius part forming a portion at least of the cavity wall opposite the orifice.

20. A piston as claimed in claim 19, wherein the apex of the peaked land is at a distance of substantially two-fifths of the radius of the larger radius portion below the plane containing the loci of the centers of the two parts of the arc.

21. A piston as claimed in claim 15 wherein the ratio of the diameter of the narrowest part of the entry throat to the diameter of the piston lies in the range 0.15:1 to 0.25:1.

22. A piston as claimed in claim 15 wherein the entry throat has a final entry portion which is tapered to be part of a cone having an apex angle of about 15°.
